(57) **CLAIM**

The ornamental design for a removable chassis section of a bumper assembly as shown and described.

DESCRIPTION

FIG. 1 is a front perspective view of a removable chassis section of a bumper assembly embodying our new design; FIG. 2 is a front elevation view thereof; FIG. 3 is a rear elevation view thereof; FIG. 4 is a left-side elevation view thereof; FIG. 5 is a right-side elevation view thereof; FIG. 6 is a top plan view thereof; and, FIG. 7 is a bottom plan view thereof.

The broken lines depict features of the removable chassis section of a bumper assembly that form no part of the claimed design.
